UNITED STATES PATENT OFFICE.

THOMAS P. PYE, OF EVERETT, WASHINGTON.

AUTOMATIC WOOD-SAW.

No. 909,454.

Specification of Letters Patent. Patented Jan. 12, 1909.

Application filed December 24, 1907. Serial No. 407,947.

To all whom it may concern:

Be it known that I, THOMAS P. PYE, a citizen of the United States, residing at Everett, in the county of Snohomish and State of Washington, have invented a new and useful Automatic Wood-Saw, of which the following is a specification.

This invention has reference to improvements in automatic wood saws, and its object is to provide a means for cutting wood into predetermined lengths.

The invention is designed more particularly for the cutting of logs or cord wood into any desired length, or for the cutting of other wood into definite lengths.

The invention is designed to be used, though not necessarily confined to use, in connection with a circular saw mounted to be moved to pass the end of a conveyer upon which is carried a log or logs, or other form of wood, to be cut into shorter lengths, either for use in stoves or such lengths that may be split into kindling wood, or for any other purpose.

The present invention is more particularly directed to means whereby the log or stick, which is advanced for a predetermined distance, is then tightly clamped in place while being cut, as will be best understood by reference to the following detailed description, taken in connection with the accompanying drawings, forming part of this specification, in which,—

Figure 1 is a plan view of the machine. Fig. 2 is a side elevation thereof. Fig. 3 is an elevation at the saw end of the machine, and Figs. 4 and 5 are detail views.

Referring to the drawings there is shown a frame 1 of suitable shape to support the various parts of the structure. Mounted in suitable journal bearings 2 on the frame is a power shaft 3 to which is secured near one end a pulley 4 for the application of power through the intermediary of a belt coming from a suitable source. Neither the belt nor the prime mover is shown, but it will be understood that any suitable source of power, such as a steam engine, explosive engine, electric motor, or windmill may be used. Mounted upon the framework 1 in other suitable journal boxes 2 are two other shafts 5, 6, parallel with the drive shaft 3. Upon the shaft 5 is a belt pulley 7, and

upon the shaft 3 is a smaller belt pulley 8 coupled to the pulley 7 by means of a suitable belt 9 indicated in dotted lines, the parts being proportioned so that the shaft 5 will rotate at a slower speed than the shaft 3. Fastened upon the shaft 5 at the end remote from that carrying the pulley 7 there is a friction wheel 10 engaging a larger friction wheel 11 on the shaft 6, so that the last-named shaft receives motion from the shaft 5, but will rotate at a slower speed.

The shaft 6 extends at one end beyond the frame 1 and there carries a beveled pinion 12 meshing with a beveled pinion 16 on a horizontal shaft 17 extending along the side of the frame at right angles to the direction of the shafts 3, 5 and 6, and this shaft is supported in suitable journal bearings 18 fast on the frame 1, the end of the shaft 17 remote from the bevel pinion 16 carrying a disk 19 from the face of which projects a pin 20 in the form of a roller mounted on a stud. Adjacent to the frame 1 is another frame 21 upon which is mounted a belt carrier 22 provided at suitable points with cross slats 23 which may be made of iron or other metal strips suitably shaped for the purpose, and at its ends with sprocket chains 24 supported by sprocket wheels 25 mounted on shafts of which the end shaft 26 only is shown, and this shaft has journal bearings 27 in the frame 21. The shaft 26 extends beyond one side of the frame 21 toward the frame 1 and there carries a sprocket-wheel 28 connected to another sprocket wheel 29 on a shaft 30 by a suitable sprocket chain 13, and on the shaft 30 there is secured a star-wheel composed of a hub 31 carrying a number of equally disposed radial arms 32 in the path of the pin 20 of the disk 19, as best shown in Fig. 5. Of course any other suitable means for transmitting motion to the conveyer may be used.

Upon the shaft 3 there is secured a belt wheel 33 about midway of the length of the shaft and pivoted to cross beams 34 in the main frame on each side of the wheel 33 are the two ends of the side bars of the frame 35, the pivot points being indicated at 36; the other ends of the frame 35 are provided with journal bearings 37 for a saw arbor 38. There is a circular saw 39 mounted upon

this arbor at one side of the frame 25, and at an intermediate point the saw arbor carries a belt pulley 40 connected to the belt wheel or pulley 33 by a suitable belt 41, indicated in dotted lines.

Straddling the belt wheel 33 are two arms 42, 42, each connected at one end to the side bars of the frame 45 between the pivot 36 and the saw arbor. These two arms are 5 ultimately joined, as shown at 43. Mounted upon the shaft 6 is a cam 44 arranged to engage a roller 45 carried by a bar 46, the upper end of which is pivotally connected to the end 43 of the lever, just described. The 10 lower end of the bar 46 is slotted longitudinally, as shown at 47, to straddle the shaft 6. On the shaft 6 there is another cam like the cam 44 and another upright bar 48 like the bar 46. The upper end of the bar 48 is pivotally connected, as indicated at 49, to one end of a lever 50 fulcrumed in a post 51 rising from one of the cross beams 34 of the main frame. Attached to the further end of the lever 50 is a spring arm 52 which may 15 be made up of a number of superposed leaf springs, as indicated, and at its free end the spring arm 52 carries a yoke 53 at about the center point thereof, and this yoke is in the shape of a bow having its ends joined by a chain 54, or other suitable strand. The lever 20 50 and spring arm 52 are of such length and so located that the chain or strand 54 is located over the delivery end of the conveyer 22.

30 Now, let it be assumed that power is applied to the pulley 4 in any suitable manner, and that the parts are properly timed in operation, and, assuming that one or more logs of wood, or at least wood in a form adapted 35 to be divided up into smaller sizes, is placed upon the conveyer 22, then the operation of the machine is as follows:

The rotation of the shaft 3 under the action of power transmitted to the belt pulley 45 4 imparts a rotative movement to the saw 39 through the belt 41. At the same time, motion is imparted to the shaft 5, and from thence to the shaft 6, from whence motion is ultimately imparted to the shaft 17, and 50 the pin 20 is brought into contact with one of the arms 32, thus rotating the shaft 30 one quarter of a revolution and thereby advancing the conveyer 22 a certain predetermined distance, which distance will equal the 55 length into which the logs or other wood are to be cut. As soon as the log has been advanced and the conveyer has come to rest, the cam actuating the lever 50 becomes active and the arm 52 is lowered until the 60 chain 54 clamps the log or stick down upon the conveyer. As soon as this occurs, the cam actuating the arm 42, 43 becomes active to raise the end connected with the bar 46, thus moving the saw frame 35 around its

pivots 36 in the direction to depress the saw 65 and force it through the wood of the log or stick until the desired piece is severed therefrom. Now, the cam 44 rides from under the roller 45, thus releasing the bar 46, and the saw immediately rises to its normal position, which is an elevated position, out of the path of the logs or sticks on the conveyer. It will be observed that the pivot points of the frame 35 are to one side of the shaft 3, and nearer to the arbor 38 than is the shaft 70 75 3. The result of this is that when the frame 35 is depressed, the belt 41 is put under tensile strain, thus tightening the belt, when the saw is called upon to do work, so that when the saw is elevated, or when the whole 80 structure is at rest, this belt need not be under any particular strain. Not only is the life of the belt 41 thereby increased, but the tendency of the belt is to maintain the saw frame in the elevated position and to return 85 it thereto when the saw is depressed. In order that the return of the saw to its normal elevated position may be assured, the arm 43 is continued back of the upright 46, as indicated at 55, and has there applied to 90 it a counterweight 56 which may be made adjustable by means of a screw 57.

As soon as the saw has finished its work and has returned to its normal position, the pin 20, which during the operation described 95 has continued to move about the axis of the shaft 17, again comes in contact with an arm 32, and the conveyer is advanced another step. But, in the meantime, the cam controlling the lever 50 has permitted the 100 latter to rise, so as to carry the chain 54 out of contact with the log or stick. As soon as the log has been again advanced, it is again clamped by the chain 54, and the saw is again lowered. Thus the cycle of operation 105 is continuous, so long as power is applied to the pulley 4 and logs or sticks of wood are placed upon the conveyer 22.

The action of the entire machine is automatic, and the only attention required is the 110 placing of the logs or sticks upon the conveyer. Thus, cord wood or longer pieces of wood in the form of logs may be readily cut up into stove lengths or into lengths adapted to be again divided into kindling wood, 115 or other forms of wood may be readily divided into such lengths as may be desired.

By suitably proportioning the sprockets 28 and 29, the extent of travel of the conveyer 22 under each impulse of the pin 20 120 may be regulated so that the lengths of the blocks into which the sticks or logs are cut may be determined.

The cam acting on the lever 50 is not identical with, though like the cam 44, since 125 it must be proportioned and timed in operation to move the lever 50 in proper time relation to the saw-operating means. To facili-

tate the return of the lever 50 to normal position an adjustable counterweight 14 is provided.

I claim:—

- 5 1. In a wood sawing machine, a conveyer, and a clamp coacting therewith, said clamp having a member for engaging the wood consisting of a spring bow, and a flexible strand connecting the ends of the bow.
- 10 2. In a wood sawing machine, a conveyer, and a clamp coacting therewith, said clamp having a member for engaging the wood consisting of a spring bow, and a chain connecting the ends of the bow.
- 15 3. In a wood sawing machine, a conveyer, and a clamp coacting therewith, said clamp being provided with a spring arm, and a member carried by said arm consisting of a spring bow and a flexible strand connecting the ends of the bow.
- 20 4. In a wood sawing machine, a conveyer, a clamp coacting therewith comprising a clamping head, a spring arm carrying the same and a lever carrying the spring arm, and means for moving the lever about its pivot to bring the clamping head into and out of operative relation to the conveyer.
- 25 5. In a wood sawing machine, a conveyer, a clamp coacting therewith comprising a clamping head, a spring arm carrying said head, and a pivoted lever carrying the spring

arm, a counterweight for the lever at the end remote from the spring arm, and means for positively moving the lever against the action of the counterweight to bring the 35 clamping head into operative relation with the conveyer.

6. In a wood sawing machine, a conveyer, a clamp coacting therewith having a clamping head comprising a spring bow and a 40 flexible strand connecting the ends of the bow, a spring arm carrying the clamping head, a pivoted lever carrying the spring arm, and means for operating the lever.

7. In a wood sawing machine, a conveyer, 45 a clamp coacting therewith and comprising a spring arm carrying a spring bow and a flexible strand connecting the ends of the bow, a pivoted lever carrying the spring arm, a counterweight on said lever at the 50 end remote from the clamping head, and means for positively moving the lever in a direction opposed to the action of the counterweight.

In testimony that I claim the foregoing 55 as my own, I have hereto affixed my signature in the presence of two witnesses.
